COMBINED CREDENZA AND EXTENSION TABLE

Abe J. Gaines, Glencoe, Ill., assignor to Saginaw Furniture Shops, Inc., Chicago, Ill., a corporation of Michigan

Application March 29, 1954, Serial No. 29,753

Term of patent 14 years

(Cl. D33—13)

Fig. 1.

Fig. 2.

Fig. 3.

Fig. 1 is a perspective view of a combined credenza and extension table embodying my new design.

Fig. 2 is a perspective view of the combined credenza and extension table shown in Fig. 1 in partially open condition.

Fig. 3 is a fragmentary top plan view of the outer corner of a drawer of the article shown in the preceding figures.

Fig. 4 is a fragmentary side elevation of the free edge of a door of the device shown in the preceding figures illustrating the handle element.

I claim:

The ornamental design for a combined credenza and extension table, as shown.
